UNITED STATES PATENT OFFICE.

JOHN ZELENÁK, OF BATTLE CREEK, MICHIGAN.

FOLDING CAMP-TABLE.

1,147,353.

Specification of Letters Patent. Patented July 20, 1915.

Application filed March 22, 1915. Serial No. 16,096.

To all whom it may concern:

Be it known that I, JOHN ZELENÁK, a subject of the King of Hungary, residing at Battle Creek, in the county of Calhoun and State of Michigan, have invented certain new and useful Improvements in Folding Camp-Tables, of which the following is a specification.

This invention relates to new and useful improvements in folding camp tables.

The primary object of the present invention is the provision of a foldable table adapted to be positioned in the form of a box for storage purposes when not desired for use.

A further object of the device is to provide a table having four corner legs and a centrally positioned binding leg, the entire structure being foldable into box formation with the five legs positioned inclosed therein.

A still further object is to provide a table especially designed for camping purposes and having the top formed in foldable sections, the said sections having retaining devices for securing the top in an unbroken plane, the sections however being foldable into closed box form for holding the corner legs secured to the adjacent sections of the table top and the center leg detached from its clamping position.

With these general objects in view and others that will appear as the nature of the invention is better understood, the same consists in the novel combination and arrangement of parts hereinafter fully described, illustrated in the accompanying drawings and pointed out in the appended claims.

In the drawings forming a part of this application and in which like designating characters refer to corresponding parts throughout the several views:—Figure 1 is a perspective view of the device set up as a table. Fig. 2 is a bottom plan view thereof. Fig. 3 is a perspective view of the device in its closed position. Fig. 4 is a perspective interior view of the lower side of an end portion of the device in its closed position with some of the elements broken away. Fig. 5 is an enlarged detail sectional view through two of the corner legs and the adjacent portion of the table top with said legs in their folded position. Fig. 6 is a longitudinal sectional view of one of the retaining bolts of the top sections. Fig. 7 is an inverted perspective

view of a corner portion of the table looking at the under side thereof. Fig. 8 is a similar view of the central portion of the table, and Fig. 9 is a perspective view of a modified form of locking bolt for the table top sections.

Referring more in detail to the drawings, the complete table top 10 of the device is formed in foldable sections and comprises two equal portions or halves 11 and 12 connected together by the hinges 13. Each of the said halves is provided with two of the corner legs 14 of the table while a centrally positioned clamping leg 15 is conjointly carried by the said two halves. The top member of each of the table halves 11 and 12 is identically formed of a central rectangular leaf 16 having oppositely positioned side leaves 17 hinged to the underneath side thereof by means of hinges 18 and 19, while the corner legs 14 of each of the said table halves are secured, one to the under side of each of the said side leaves 17 as best illustrated in Fig. 2. Retaining bolts 20 are carried by the under face of the leaves 16 and are adapted to be projected into loops 21 of the said side leaves 17 for the purpose of retaining the side leaves in an alining plane with the leaf 16. Each of the central leaves 16 is also provided with side leaves 22 which are hinged as at 23 to the said leaves 16. A double bolt member 24 is carried by the leaves 22 and adapted to engage a double keeper 25 upon the under side of the leaves 16 for the purpose of retaining the terminal or end ones of the leaves 22 in alinement with the leaves 16.

Each of the tops of the table halves is provided at each outer corner with a square corner section 26 which is hinged as at 27 to the sections 22 and is inwardly foldable thereagainst but is adapted to be held in proper alinement with the adjacent top sections by means of the bolts 28 carried by the leaves 17 and engaging straps 29 of the said corner sections 26. Similar corner sections 30 are provided at the inner corners of the top of each of the table sections and the same are hinged as at 31 to the adjacent edges of the leaves 17, while interengaging bolts 32 and loops 33 are carried by the corner sections 30 for retaining the said sections in a single plane when the table top is in its operative position. With this arrangement of table halves it will be seen that the top of each half will form a rectangular

and substantially square board or composite leaf when the separate bolts 20 and 28 are in their locked positions and that the separate tops of the table halves are retained in 5 alignment for forming the complete table top as illustrated in Figs. 1 and 2 of the drawings by means of the said bolts 32 and also by slidably positioning the central leg 15 with its top plate 34 engaging beneath 10 the receiving cleats 35 secured to the lower face of the leaves 22 and whereby the central leg plate 34 connects the centrally positioned hinged together leaves 22.

The form of bolt illustrated in Fig. 9 may 15 be employed if desired which consists of a sliding plate 36 having a slide rod 37 linked thereto, the said plate slidable through a block 33 and the rod slidable through a loop 39 carried by the said block.

20 With this form of device set up as a table as shown in Fig. 1, the same may be readily folded to its box form as illustrated in Fig. 3 by slidably removing the central leg 15 and then releasing all of the bolts 20, 24, 25 28 and 32. The weight of the several parts of the device will tend to hold the same in the folded position as shown in Fig. 3 and if required, a suitable strap may be positioned about the frame. The corner sections 26 and 30 are then folded inwardly 30 upon the adjacent top sections to which they are hinged and then the side leaves 17 are moved inwardly upon their hinges 18 and 19, the corner legs 14 carried thereby resili- 35 ently interengaging with each other by means of the cut away portions 40 upon the inner sides of each of the said legs, the outer end leaves 22 being also folded inwardly, the said elements thus forming together a 40 four sided partial inclosure as best illustrated in Fig. 4 and having the two corner legs positioned therein. The central side leaves 22 are moved upon their hinges 13 for completing the two folded halves of the 45 table and whereupon the two halves thus formed and which comprise five sided open receptacles are moved to closed position 50 upon the hinges 13 to the form illustrated in Fig. 3 and having the separate central leg 15 loosely housed therein and forming a closed six sided box.

It will thus be seen that a folded table structure is provided which may be readily

positioned in table form and also easily 55 folded in its box form, in which latter form, the same may house other articles such as camping equipment and may be retained closed by any desired locking means, the same however not being herein illustrated.

While the form of the invention herein 60 shown and described is what is believed to be the preferred embodiment thereof, it is nevertheless to be understood that minor changes may be made in the form, proportion and details of construction without departing 65 from the spirit and scope of the invention as set forth in the appended claims.

What I claim as new is:—

1. A device of the class described comprising 70 two identically formed foldable top portions, two corner legs carried by each of the said portions, hinges connecting the said portions together, and a slidably mounted removable central clamping leg positioned beneath the two top portions when the device is in its table formation.

2. A device of the class described comprising 75 two equal sized foldable top members hingedly attached together and each comprising a central leaf, opposite side and end leaves hinged to the said central leaf, corner top sections hinged to the adjacent side and end leaves, corner legs secured to the said side leaves, locking bolts between the adjacent leaves and a slidably positioned central locking leg carried by the centrally positioned leaves.

3. A foldable table comprising two identically formed sections, each of said sections having a central leaf, auxiliary leaves provided in hinged relations and adapted for forming open topped receptacles with the said central leaves, two corner legs carried by each of said sections, hinged connections between said sections, the said corner legs 95 lying inclosed in interlocking engagement when the two sections are positioned in contact with each other in their closed box formation.

In testimony whereof I affix my signature 100 in presence of two witnesses.

JOHN ZELENÁK.
